Markel Clerk

UNITED STATES PATENT OFFICE.

ERNEST NORBERT KENNEDY, OF LONDON, ENGLAND.

COLLAPSIBLE TRUNK, SUITCASE, AND THE LIKE.

Application filed April 17, 1925. Serial No. 23,767.

This invention relates to trunks, suitcases, and the like of the kind which comprises two telescopically arranged parts adapted to be connected together by means of extensible fastening devices, so that when the trunk or suitcase has been packed, the two parts thereof may be collapsed, or pressed one toward the other, so as to securely hold the contents against undesired movement, the fastening devices being so arranged as to hold the two parts of the trunk, suitcase or the like in any telescoped or collapsed condition of the parts thereof.

A trunk or suitcase of this kind has been disclosed in my prior Patent No. 1,508,142 issued September 9, 1924.

In trunks or suitcases of this kind some difficulty may be experienced in opening or swinging the upper part or lid about the extensible hinge devices between the same and the lower part of the trunk or suitcase, particularly in the fully telescoped or collapsed condition of the parts, if the parts fit closely together and the front walls thereof are perpendicular to the top and bottom walls respectively of said parts. This difficulty is avoided in the patent above mentioned by making the parts of the suitcase of rhombic cross section with the front and rear walls of the parts parallel but inclined with respect to the top and bottom walls.

The object of the present invention is to provide a form or forms of trunk, suitcase, or the like of the telescopic or collapsible kind indicated above, having the parts thereof arranged so that the one part or lid may be readily swung about the hinge devices between the same and the other part, even in the fully telescoped or collapsed condition of the parts.

According to the invention one or the other of the two parts of the trunk, suitcase or the like is provided with a front wall which is movable to a limited extent in order that it may give or yield sufficiently to enable the upper part or lid of the trunk or suitcase to be swung about the hinge members to open the trunk or suitcase. If desired the front walls of both parts of the trunk or suitcase may be made movable in this way.

The invention is illustrated in different forms thereof in the accompanying drawings, in which:

Figure 1 is a diagrammatic representation

of a collapsible or telescopic suitcase having 55 the front wall of the lower part thereof made movable in accordance with the invention.

Fig. 2 is a similar view of a modified form 60 of suitcase having the front wall of the upper part or lid of the suitcase pivotally movable.

Fig. 3 is a similar view of another modified 65 form of suitcase having the front wall of the upper part or lid slidably movable, and

Fig. 4 is a view of a further modification 70 in which the front walls of both parts of the suitcase are made movable.

Referring to Figure 1 the suitcase comprises the lower part 1 and the upper part or lid 2, the latter being arranged to fit over the lower part and to assume different telescoped 75 or collapsed positions relatively thereto, according to the extent to which said lower part is packed with clothes or the like.

The two parts 1 and 2 of the suitcase are adapted to be connected together by means 80 of extensible fastening devices which as shown comprise extensible hinge devices 3 at the rear of the suitcase and extensible locking devices 4 at the front of the suitcase. These extensible fastening devices may be 85 of any suitable form, for example the form shown in the prior patent above referred to, or the form shown in the copending application Serial No. 23,768, filed April 17, 1925. So far as the present invention is concerned 90 it is sufficient to state that these extensible devices comprise two parts 5 and 6, one of which is provided with a ratchet rack element while the other is provided with a pawl element adapted to engage said rack element in 95 the closed or locked condition of the parts shown in Fig. 1 in order to prevent extension of said fastening devices and to hold the parts of the suitcase securely in the telescoped or collapsed condition thereof. The 100 parts 5 of these fastening devices are secured to the upper part or lid of the suitcase and the parts 6 of the hinge devices are pivotally connected to hinge members 7 secured to the lower part of the suitcase. The parts 6 of the locking devices 4 have pivotally connected to the lower ends thereof hasp members 8 adapted to coact with suitable locks 9 secured to the lower part 1 of the suitcase.

When the hasps 8 are released from the locks 105 and turned by suitable springs into a position perpendicular to that shown the pawl elements are released from the rack elements

so that the parts 6 may be extended, and when the lid 2 is swung about the hinge members 7 the pawls of the parts 6 of the hinge devices are released from their rack elements 5 so that the parts 5 and 6 may be extended. When the lid 2 is swung back into the closed position shown in Fig. 1 and the hasps 8 are engaged with the locks 9 the pawl elements are in engagement with the rack elements 10 and the lid 2 may be pressed down to such extent as may be necessary to securely hold the contents of the suitcase between the two parts 1 and 2 thereof, the pawl elements engaging the ratchet racks to securely hold the 15 upper part or lid against upward movement.

According to the present invention the front wall 10 of the lower part 1 of the suitcase is made movable relatively to the remainder of said part and as shown it is 20 hingedly connected in any suitable manner at its lower edge with the bottom wall of said part 1 so as to be capable of an inward or rearward movement. The front edges 11 of the side walls 12 of said lower part 1 will 25 be upwardly or rearwardly inclined as indicated to permit the desired movement of said front wall 10, and the spaces left between the ends of said front wall 10 and the front edges 11 of the side walls 12 may be closed in any 30 suitable manner as, for example, by providing the collapsible sections 13 between said side walls and said front wall, which sections may also serve to limit the forward or outward movement of said front wall.

35 It will be understood that with this arrangement of the parts, when the upper part or lid is swung about the hinge members 7 to open said lid the front wall 10 of the lower part 1 will give or yield inwardly or rearwardly so as not to interfere with the free 40 swinging or opening movement of the upper part or lid 2. The dot and dash lines indicate the lid in the fully collapsed position thereof and the dotted line 14 indicates the 45 path taken by the lower part of the front wall 15 of the lid. If desired suitable springs or the like may be provided, for example between the front wall 10 and the lower wall of the part 1, normally tending to hold the front wall 10 in its outermost position as 50 shown in Fig. 1.

In the modified form of suitcase shown in Fig. 2 the front wall 15 of the upper part or lid 2 of the suitcase is made movable, being hingedly connected in any suitable manner with the top wall of said lid, so as to yield or move outwardly about said hinge connection from the full line position shown in Fig. 2 to a position such as that indicated in the 60 dotted lines in the figure. The side edges of the front wall 15 may if desired be connected with the front edges of the side walls 16 of the lid, for example by means of collapsible sections such as the sections 13 shown in 65 Fig. 1, or as shown the said front wall 15 may

be provided with side flaps 17 arranged to overlie the front parts of the side walls 16. If desired means may be provided, such as the pin and slot connections 18, between said side flaps 17 and side walls 16, to limit the 70 outward or swinging movement of said front wall 15.

It will be readily understood that when the upper part or lid is swung about the hinge members 7 the front wall 15 of the lid will 75 give or yield to such extent as may be necessary in order to enable said lid to be readily swung or moved into the open position thereof.

In the modified form of suitcase shown in Fig. 3 the front wall 19 of the upper part or lid 2 of the suitcase is arranged to have a forward or outward sliding movement relatively to the remainder of said part or lid. Said front wall 19 is shown as provided with 80 side flaps 20 arranged to overlie the side walls 21 of the lid and pin and slot connections 22 are provided between said side flaps and said side walls serving to guide and to limit the forward or outward movement of the side 85 wall 19. The upper edge of the front wall 19 and the front edge of the top wall of the part or lid 2 may be connected by means of a collapsible section so as to avoid having a space between these edges when the front 90 wall is moved outwardly.

It will be readily understood that when the upper part or lid is swung about the hinge members 7 the said front wall 19 will yield or give outwardly sufficiently to enable said 100 part or lid to be readily moved into the open position.

In the modified form of suitcase shown in Fig. 4 both the front wall 10 of the lower part 1, and the front wall 15 of the upper part or lid 2 are made movable. The wall 10 of the lower part 1 may be movably arranged in the same manner as described with reference to Fig. 1 and the wall 15 of the upper part or lid may be arranged in the same manner as described with reference to Fig. 2, or in the manner described with reference to Fig. 3. With both walls arranged to yield or move in this way the extent of movement of each will be less than when only one wall is arranged to be movable.

It will be understood that the arrangements shown in the drawings are somewhat exaggerated for the purpose of clearly indicating the necessary movements and that in 110 the actual suitcase or trunk the movements of the parts necessary will be relatively small.

It will also be understood that while the invention has been specifically described as applied to a suitcase it may be equally well 125 employed in connection with trunks or the like, the only difference in the case of a trunk being in the depth of the lower part 1 thereof. In the case of a trunk arranged according to Figures 1 and 4 it may only be necessary 130

to make movable the upper part of the front wall of the lower part of the trunk depending upon the extent to which the upper part or lid is made to telescope over the lower part 5 of the trunk.

What I claim and desire to secure by Letters Patent is:—

1. An expandible trunk, suitcase, or the like, comprising two telescopically arranged 10 parts, respectively comprising a top wall and a bottom wall, and side and end walls connected thereto, extensible hinge devices connected at opposite ends thereof to the rear walls of said parts and non-extensible in the 15 closed position of said parts, one of said parts having the front wall thereof movable to a limited extent sufficient to permit the upper or lid part to be swung about said hinge devices in any telescoped position of said parts, 20 means between said movable front wall and the adjacent walls of the same part for closing the space between said walls in all positions of said front wall, and extensible fastening devices on the front wall of one of said

parts adapted to coact with latching means 25 on the front wall of the other part.

2. An expandible trunk, suitcase, or the like, as claimed in claim 1, wherein means are provided between said movable front wall and the adjacent side walls of the same part 30 for limiting the movement of said front wall.

3. An expandible trunk, suitcase, or the like, as claimed in claim 1, wherein the front wall of the lower or inner telescopic part is inwardly or rearwardly movable. 35

4. An expandible trunk, suitcase, or the like, as claimed in claim 1, wherein the front wall of the lid or upper telescopic part is outwardly or forwardly movable.

5. An expandible trunk, suitcase, or the like, as claimed in claim 1, wherein the front walls of both of said telescopic parts are movable, the wall of the lower or inner part being inwardly movable, and the wall of the upper part or lid being outwardly movable. 40 45

In testimony whereof I affix my signature.

E. NORBERT KENNEDY.
